MOTOR VEHICLE SEMAPHORE

Filed June 29, 1929

UNITED STATES PATENT OFFICE

RALPH A. CHURCHILL, OF SPOKANE, WASHINGTON

MOTOR-VEHICLE SEMAPHORE

Application filed June 29, 1929. Serial No. 374,717.

My invention relates to motor vehicle semaphores and certain objects of the invention are to provide simple and novel means whereby the direction arrow of the device may be pivotally moved in both a horizontal and vertical direction to indicate the direction in which the driver of the vehicle intends to turn and also the intention of the driver to stop the vehicle. Further objects of the invention are to provide means for adjusting the device to vertical position whereby it is adapted for installation on the tops of vehicles of various slants together with other novel details of construction herein-
15 after set forth.

With the above and other objects in view which will appear as the description proceeds, the invention consists of the novel construction, adaptation, combination and arrangement of parts hereinafter described and claimed. These objects are accomplished by devices illustrated in the accompanying drawings; wherein:—

Figure 1 is a view in side elevation showing the device mounted on the top of a motor vehicle and showing the stop position of the direction arrow in dotted lines;

Fig. 2 is top plan view of the same and showing the position of the direction arrow to indicate a right and a left turn;

Fig. 3 is an enlarged detail view of the device in vertical section taken substantially on a broken line 3, 3 of Fig. 2 with parts in elevation and showing the stop position of the direction arrow in dotted lines;

Fig. 4 is a view in transverse vertical section taken on a broken line 4, 4 of Fig. 3; and

Fig. 5 is a view in horizontal section taken on a broken line 5, 5 of Fig. 3.

Referring to the drawings throughout which like reference numerals designate like parts, the numeral 5 indicates a tubular member which is ordinarily mounted in an upstanding position with its upper portion projecting through the top of a vehicle and its lower portion terminating in a position where it may be conveniently reached by the driver of the vehicle. A handle 6 is fixedly mounted on the lower end of said

tube and a direction arrow 7 is pivoted at 8 to the upper end of the tube in such position that it may move in a vertical plane which passes through said handle. Thus, the arrow and handle being in the same plane, the position of said handle will serve as a means for indicating to the driver the direction in which the arrow points at all times.

The tubular member 5 passes through a relatively large hole 9 in a plate 10 which plate is adapted to be secured to the underside of the vehicle top as clearly shown in the drawings. Said plate is provided with upstanding flanges 11 and a rectangular block 12 is pivotally mounted between said flanges by means of a large wrist pin 13. The tube 5 passes through said block and wrist pin and a split 14 extending to the center of said block with a screw 15 passing therethrough provides means whereby frictional engagement of said tube by said block may be increased or decreased as desired. The block is held between the flanges by bolts 16 and a collar 17 secured to said tube by a set screw 18 prevents said block from slipping downwardly.

A dome shaped housing 18, open at both its upper and lower ends, has a flanged base 19 formed on its lower portion whose dimensions correspond to those of the plate 10. Said housing is placed on the upper side of the vehicle top in position to enclose the block 12 and its associated parts and with its base portion in registry with said plate 10. Bolts 20 passing through said plate and flange retain the housing securely in place on the vehicle top.

A hemispherical cover member 21 corresponding in shape with the dome portion of the housing 18 is mounted thereon with a center hole having an upstanding neck 22 through which the tubular member 5 passes. A cap member 23 with a slanting exterior top portion is centrally provided with a hole 24 through which said tubular member passes and is also provided with a recess 25 in its underside to receive the neck 22. A set screw 26 holds said cap in place and a spring 27 interposed between said neck and recess 25.

retains the cover member in resilient engagement with the housing 18.

It will now be obvious that the tubular member 5 may be pivotally turned on its axis by means of the handle 6 to any of the positions shown in Fig. 2 of the drawings. It will also be obvious that said tubular member may be adjusted to vertical position for vehicles with tops of different slant by loosening the bolts 16 pivotally shifting said tube on its axis or wrist pin 13 and again tightening said bolts. Owing to the downward slant and curvature of the cap member 23, cover member 21, and housing 18 and also to the fact that said members are disposed in overlapped relation the device is weather proof as will be understood.

The means for shifting the arrow 7 from the full line to the dotted or stop position shown in Figs. 1 and 3 of the drawings comprises wires 27 and 28 fastened to said arrow at points 29 and 30 and extending downwardly into the tube 5. The wire 27 is secured to the upper end of a rod 31 slidably disposed within the tubular member and provided at its lower exterior end with a knob 32 for manipulation. Said rod is also provided with a pin 33 which slides in a slot 34 with an offset portion 35 at its lower end. The lower end of the wire 28 is secured to a spring 36 that is mounted within said tubular member having its lower end secured thereto.

The tension of the spring 36 is so adjusted in its connection with the wire 28 that the arrow 7 will be normally held in a horizontal position with a shoulder 37 thereon in engagement with the tubular member 5. By overcoming said tension with a downward pull on the knob 32 the wire 27 will draw the forward end of said arrow downward to the dotted position and then by turning said knob the pin 33 may be brought to rest in the offset slot portion 35 whereby the arrow may be retained in the tilted or stop position until released.

The arrow 7 is provided with rear horizontal fins 38 and the word Stop is printed on the undersides thereof so that when said arrow slants to the stop position the word Stop will be visible from the rear. Referring to Figs. 4 and 5 of the drawings, I usually provide a light 39 that is positioned to illuminate said word. This light may be mounted on arms 40 projecting from the housing 18 and has circuit wires leading to the lighting system of the vehicle. A cone 41 is formed on the arrow over its pivotal connection 8 for the purpose of preventing water from entering the top of the tubular member 5 as will be understood.

It will now be apparent that I have provided a simple and direct acting device that will indicate all the signals used in driving a motor vehicle and which embodies means for adjustment to various vehicles as well as

means for preventing water from entering the vehicle.

Having thus described my invention, it being understood that minor changes may be resorted to in its construction without departing from its scope and spirit, what I claim and desire to secure by Letters Patent of the United States is:—

1. The combination with a motor vehicle, of a motor vehicle semaphore comprising a tubular member mounted to project through the top of the vehicle, said tube adapted to be turned on its axis, means for adjusting said tube to the vertical position, a direction arrow pivotally mounted on the upper end of said tube, and a handle for the lower end of the tube disposed in the same vertical plane with the direction arrow.

2. The combination with a motor vehicle, of a motor vehicle semaphore comprising a tubular member mounted to project through the top of the vehicle, said tube adapted to be turned on its axis, means for adjusting said tube to the vertical position, a direction arrow pivotally mounted on the upper end of said tube, a handle for the lower end of said tube disposed in the same vertical plane with the direction arrow, means for inclining said arrow forward, means for retaining said arrow in the inclined position, and spring means for causing said arrow to return to its normally horizontal position.

3. The combination with a motor vehicle, of a motor vehicle semaphore comprising a tubular member mounted to project through the top of the vehicle, said tube adapted to be turned on its axis, means for adjusting said tube to the vertical position, a direction arrow pivotally mounted on the upper end of said tube, a handle for the lower end of said tube disposed in the same vertical plane with the direction arrow, means for inclining said arrow forward, means for retaining said arrow in the inclined position, spring means for causing said arrow to return to its normally horizontal position, means for illuminating said direction arrow, and means for preventing the entry of water through said tube and its mountings.

In testimony whereof I affix my signature.

RALPH A. CHURCHILL.
